Primary Examiner—Janice E. Seeger*Attorney, Agent, or Firm*—Charles H. Schwartz; Ellsworth R. Roston[57] **CLAIM**

The ornamental design for a mirror, as shown and described.

DESCRIPTION

FIG. 1 is a front elevational view of a mirror showing my new design;

FIG. 2 is a side elevational view, the opposite side being substantially a mirror image thereof; and,

FIG. 3 is a top plan view, the bottom being substantially identical thereto.

The rear of the mirror is plain and unadorned.
